United States Patent Office

Des. 208,319
Patented Aug. 15, 1967

208,319

CEREAL BOWL OR SIMILAR ARTICLE

Irene M. Manseau, Hollis, N.Y.
(61 W. Marie St., Hicksville, N.Y. 11801)

Filed Sept. 26, 1966, Ser. No. 4,047

Term of patent 14 years

(Cl. D44—15)

FIGURE 1 is a perspective view of a cereal bowl or similar article showing my new design;

The essential features of the design are shown in full lines.

I claim:

The ornamental design for a cereal bowl or similar article, substantially as shown and described.
